JET ENGINE HAVING AN AIR COMPRESSOR
DRIVEN SOLELY BY A FUEL GAS TURBINE

Edward A. Phaneuf, Kansas City, Mo.

Application May 16, 1947, Serial No. 748,446

1 Claim. (Cl. 60—35.6)

1

This invention relates to a hydrogen jet motor adapted for use on airplanes.

It is an object of the present invention to provide a jet motor adapted to be operated by hydrogen wherein the hydrogen gas leaving a container under pressure will operate a turbine wheel to effectively mix the hydrogen with the air drawn into a chamber and prior to its outlet to the jet chambers where the hydrogen and air are ignited.

Other objects of the present invention are to provide a hydrogen jet motor which is of simple construction, inexpensive to manufacture and efficient in operation.

For other objects and for a better understanding of the invention, reference may be had to the following detailed description taken in connection with the accompanying drawing, in which:

Fig. 1 is a side elevational view of my jet motor with a portion broken away to show the interior of the same.

Fig. 2 is a longitudinal cross-sectional view of my jet motor.

Fig. 3 is a front end view of my jet motor.

Fig. 4 is a rear end view of the motor.

Figs. 5, 6, 7 and 8 are respectively transverse cross-sectional views taken respectively on lines 5—5, 6—6, 7—7 and 8—8 of Fig. 2 and looking in the direction of the arrows thereof.

Referring now to the figures, 15 represents an outer casing of tear drop configuration having an open forward end or air inlet 16 and a rear exhaust outlet 17. This casing is adapted to be connected to some part of an airplane. In the inlet opening is a transversely extending vane structure 18 in which is journalled a shaft 19 extending throughout the casing and journalled at its opposite end in a central bracket 21 having arms 22 connected with the exterior of the chamber 34. The bearing for the shaft 19 is indicated at 23. Surrounding a portion of the shaft is a casing 24 in which is disposed a turbine wheel 25 against which hydrogen gas under pressure is projected from nozzles 26 at the end of a coil of pipe 27 leading to a fuel supply of hydrogen as indicated at 28. The hydrogen after causing the wheel 25 to turn becomes free in the casing 24 and will be impelled by blades 31 through openings or passages 32 extending to combustion chambers 33 in chambers 34. The chambers 34 are a continuation of air passages 35 and within these chambers the hydrogen and air are mixed and ignited by an electric spark plug 36. The gas jets are created in outlet passages 37 extending from the chambers 34 and will react to cause a thrust in the space in rear of the motor by means of the exhaust or reaction nozzle 17. The turbine wheel accordingly drives the shaft 19 and on this shaft are air impelling blades 38 adapted to drive the air under pressure through the air passages 35.

2

This air is taken through the central inlet at the forward end of the motor.

The combustion chambers 33 are perforated as indicated at 41. By having the hydrogen supply pipe coiled about the casing 24, the hydrogen will be adequately pre-heated so that maximum gas pressure is obtained.

There are four combustion chambers within the casing 15 and it shall be understood that a larger number of these chambers might well be utilized.

The chamber 24 is fixed against rotation by welding the same to the bracket 21 as indicated at 42.

While various changes may be made in the detail construction, it shall be understood that such changes shall be within the spirit and scope of the present invention as defined by the appended claim.

I claim:

A jet motor comprising an outer casing having a forward air inlet and a rear reaction nozzle, a supporting vane structure secured to the outer casing adjacent the air inlet, a bracket in the outer casing rearwardly of the vane structure, a shaft journalled in the vane structure and bracket, an inner casing surrounding a portion of the shaft and secured to the bracket, a turbine wheel fixed to the shaft within the inner casing, a source of fuel under pressure, fuel nozzles located immediately in front of the turbine blades and entering the inner casing to direct fuel under pressure upon the turbine wheel to cause its rotation, an outlet pipe from the inner casing, a combustion chamber at the end of said outlet pipe, impeller plates on said shaft for receiving the exhaust from the turbine and positioned within the inner casing for causing the flow of fuel from the turbine through the outlet pipe, air impelling blades on the shaft in the rear of the air inlet, an air passage extending from the air impelling blades to said combustion chamber for passing air thereto, exhaust pipes extending from the combustion chamber, and spark plug means for igniting the fuel within the combustion chamber.

EDWARD A. PHANEUF.
